(57) **CLAIM**

The ornamental design for a camping lantern, as shown and described.

DESCRIPTION

FIG. 1 is a rear, right perspective view of a camping lantern showing my design.

FIG. 2 is a rear, left perspective view of the camping lantern in FIG. 1.

FIG. 3 is a front, right perspective view of the camping lantern in FIG. 1.

FIG. 4 is a front elevation view of the camping lantern in FIG. 1.

FIG. 5 is a rear elevation view of the camping lantern in FIG. 1.

FIG. 6 is a left side elevation view of the camping lantern in FIG. 1.

FIG. 7 is a right side elevation view of the camping lantern in FIG. 1.

FIG. 8 is a top plan view of the camping lantern in FIG. 1.

FIG. 9 is a bottom plan view of the camping lantern in FIG. 1.

FIG. 10 is an enlarged view of area “10” in FIG. 1.

FIG. 11 is an enlarged view of area “11” in FIG. 1.

FIG. 12 is an enlarged view of area “12” in FIG. 1; and,

FIG. 13 is an enlarged view of area “13” in FIG. 3.

The broken lines in the drawings are employed to show unclaimed portions of the camping lantern, and form no part of the claimed design. The dash-dot broken lines in the figures are demarcating enlarged areas and form no part of the claimed design.

1 Claim, 13 Drawing Sheets
